UNITED STATES PATENT OFFICE.

GEORGE R. WATSON, OF WATERLOO, IOWA, ASSIGNOR TO ARMSTRONG MANUFACTURING COMPANY, OF WATERLOO, IOWA.

APPARATUS FOR SHAPING DRILL BITS.

Application filed January 2, 1924. Serial No. 684,082.

To all whom it may concern:

Be it known that I, GEORGE R. WATSON, a citizen of the United States of America, and a resident of Waterloo, Black Hawk County, Iowa, have invented certain new and useful Improvements in Apparatus for Shaping Drill Bits, of which the following is a specification.

My invention relates to improvements in apparatus for shaping drill-bits, and the object of my improvement is to provide adjustable supporting-means for a drill while having its bit shaped by means of a reciprocating die, this means being devised for convenient hand operation and adjustments.

This object I have accomplished by the means which are hereinafter described and claimed, and which are illustrated in the accompanying drawings, in which Fig. 1 is a side elevation of my improved apparatus with a drill mounted thereon, parts of the supporting means being broken away, and other parts sectioned or broken away, and Fig. 2 is a top plan view of the same.

In said drawings, the numeral 1 denotes a longitudinally spaced pair of base-blocks made of concrete upon which are superposed blocks of wood, and upon these wooden blocks are bolted the transversely spaced parallel metal side-beams 2.

Upon these beams 2 near one end are alined bearing-boxes in which are journaled the end parts of a rotatable shaft carrying a belt-wheel 23 having thereon a driving-belt 24, and one face of the belt-wheel being coned for braking contact of a friction-clutch member 25. The shaft intermediate said boxes has a crank 21 with a pitman or connecting-rod 32 which is terminally connected to the middle of a powerful semi-elliptic spring 20, the ends of the spring having rod connections 33 with a reciprocable plunger or hammer-head 18, the latter carrying a detachable die-head 19.

The numeral 34 denotes inwardly directed ribs on the beams 2 and upon which are slidably mounted a gage-ring carrier 3 and a thrust-block 14. The carrier 3 and the thrust-block 14 are longitudinally spaced but are connected by means of one or more connecting bars 11 terminally mounted on studs 10 and 13 respectively projecting from said parts. For purposes of varying the amount of longitudinal separation between these parts 3 and 14, the bar 11 has a longitu-

dinal row of holes 12 to receive said stud 13 interchangeably.

The numeral 29 denotes an elongated drill of the usual type employed to drill well-holes. This drill has a diminished threaded shank upon which may be mounted a thrust-cap 30 having a pair of like annular ribs, each with one face sloped. The numeral 15 denotes a semi-cylindrical hollow body being the upper part of a thrust-block 14 whose hollow wall is shaped with ribs 16 which are mates of the other ribs 31 on the thrust-cap and to be engaged therewith for longitudinal adjustment of the thrust-cap. This permits sidewise rocking of the thrust-cap and drill without disengagement from the thrust-block in the operation of reversing the position of the drill-bit while being operated upon by the die 19.

The numeral 26 denotes a gage-ring inferiorly shaped for the offsetting of the softened heated drill-bit thereinto under the blows of the die 19. The carrier 3 has a half ring projection or rib which seats in the groove 27 around the gage-ring and also engages the part 28 thereon, so that the gage-ring is held in engagement with the carrier, but may be rocked sidewise relative thereto.

The carrier body 3 has a depending part 85 slotted upwardly from below at 5 to slidably receive a pin 6 on a lever 7 which lever is terminally pivoted at 8 to a block 9 on one beam 2. The drill having been fitted with said thrust-cap 30 and with the gage-ring to be coterminous therewith, may be laid upon the supporting means with the gage-ring on the carrier 3, the ribs 31 engaging ribs of the thrust-block. The relative position of the gage-ring and the drill are first to be determined and adjustably made by fitting the stud 13 into an appropriate hole 12 of the draft-bar 11. Then the operator may shift the lever 7 to bring the drill forwardly to a greater or less distance 100 relatively to the die 19 to permit the die to strike blows of the desired power upon the drill-bit, and the drill may be shifted rockingly sidewise back and forth reversely to permit the die to treat the bit as necessary 105 in shaping it.

Having described my invention, what I claim as new, and desire by secure by Letters Patent, is:

1. An apparatus of the character de-

110

scribed, comprising supporting-means, a spaced and connected thrust-block and gage-ring carrier mounted for detachable and adjustable support upon said supporting means, a gage-ring detachably connected to said gage-ring carrier, a thrust-cap for detachable engagement with one end of a drill and having engaging-devices thereon, said thrust-block having a plurality of engaging-devices thereon to co-mate with the engaging-devices on said thrust-cap for longitudinal adjustments therebetween, and manually operable means for shifting said connected gage-ring carrier and thrust-block to and fro.

2. An apparatus of the character described, comprising supporting-means, a spaced and adjustably connected thrust-block and gage-ring carrier mounted for detachable and adjustable support upon said supporting-means, a gage-ring to receive the bit end of a drill and detachably connected to said gage-ring carrier for rocking engagement therewith, a thrust-cap for detachable engagement with the other end of the drill and having annular ribs thereon, said thrust-block having a plurality of co-mating

half-rings thereon to engagingly and adjustably receive the said annular ribs interchangeably for longitudinal adjustment of the thrust-cap relative to the thrust-block while permitting rocking engagement of the former upon the latter, a hand-lever pivoted on said supporting-means, and a slotted projection on said gage-ring carrier, 35 said lever having a pin projection slidable in said slotted projection whereby the lever may be used to longitudinally shift said connected carrier and thrust-block to and fro.

3. In combination, a carrying-device for a drill having adjustably connected parts, a reciprocatory die-head alined with said device to operate upon an end of a tool or drill carried by said device, and means for supporting said carrying-device including co-mating annular engaging devices thereon for interchangeable adjustable engagement with mating annular engaging means mounted on the drill, permitting rocking relative movements of the drill.

Signed at Waterloo, Iowa, this 5th day of Dec. 1923.

GEORGE R. WATSON.
